(57) CLAIM

The ornamental design for a rectangular cut diamond, as shown.

DESCRIPTION

FIG. 1 is a top plan view of a rectilinear diamond cut showing my new design;

FIG. 2 is an end view of the diamond of FIG. 1;

FIG. 3 is a side elevational view of the diamond of FIG. 1;

FIG. 4 is a bottom plan view thereof;

FIG. 5 is a top plan view of a trapezoidal diamond cut showing my new design;

FIG. 6 is an end view of the narrow end of the diamond of FIG. 5;

FIG. 7 is a side elevational view of the diamond of FIG. 5;

FIG. 8 is an end view of the wide end of the diamond of FIG. 5; and,

FIG. 9 is a bottom plan view thereof.
